UNITED STATES PATENT OFFICE.

JAMES C. REED, OF BOSTON, MASSACHUSETTS.

IMPROVEMENT IN ATTACHMENTS FOR PROTECTING SLEEVES AND CUFFS OF GARMENTS.

Specification forming part of Letters Patent No. 120,324, dated October 24, 1871.

To all whom it may concern:

Be it known that I, JAMES C. REED, of Boston, Massachusetts, have invented a certain new and useful Attachment for Protecting Sleeves and Cuffs of Garments, of which the following is a specification:

The object of the invention is to preserve the cuffs and the lower portion of the arm-clothing generally from injury while washing the hands. It may be with some success also used in attending to any dirty work.

I employ vulcanized rubber of proper stiffness in the several parts, having a stiff portion to encompass the arm and extend up a little distance toward the elbow, a thin and very flexible part extending from the lower end thereof, and a highly-elastic ring, which contracts tightly around the wrist, at the lower edge.

The accompanying drawing forms a part of this specification, and represents what I consider the best form of the device.

Figure 1 is a perspective view of one mode of construction. Fig. 2 is a perspective view of a portion slightly modified in construction.

Similar letters of reference indicate like parts in both the figures.

A is a false sleeve, made preferably of about one-sixteenth of an inch in thickness, of ordinary soft, flexible, vulcanized rubber. This will afford sufficient stiffness to insure its keeping its place, extending a proper distance up the arm. *B* is a thin extension of the same, formed either in one piece therewith, or it may be oiled-silk or like material, very strongly and tightly attached thereto by cementing or otherwise. This may be only of the thickness of thin paper, but should be of the best quality of rubber or other water-proof material, and adapted to contractor gather around and completely protect the exposed edge of the shirt-sleeve or cuff. *C* is a ring or band of the thicker material, adapted to exercise an active contractile force on the wrist.

I propose in some instances to provide small loops on the exterior of the thin material *B*, and to reeve through these loops pieces of the cylindrical cord always found in the market under the name of elastic. This will allow the replacing of the contractile cord as often as may be required in long use, but it will be sufficient in most cases, and will serve a long period, if the contractile cord *C* is permanently joined to the thin material *B*. Where it is not practicable or convenient to form the whole in one piece the contractile band *C* may be cemented within a fold or turn of the former on the edge of the thin material *B*.

The cuff-protector may be kept in any suitable receptacle, or hanging by the loops *D* on a nail or other suspending-point, near the wash-stand. Before commencing to wash one is drawn over each hand and made to embrace and protect the lower end of the sleeve. When the washing is completed and the wiping is finished or nearly finished, the cuff-protectors are withdrawn and placed in position convenient for the next operation.

The stiff portion *A* may be made longer, so as to extend further up the wrist. Such a protection may be useful for book-keepers to protect the sleeve from desk-rubbing, &c.; but I prefer about the length here shown, and recommend the protectors only for temporary use.

I claim as my invention—

The within-described new article of manufacture, having a stiff ring, *A*, a thin and highly-yielding ring, *B*, and a contractile cord or edge, *C*, all formed of rubber, and adapted to serve as herein set forth.

In testimony whereof I have hereunto set my name in presence of two subscribing witnesses.

JAMES C. REED.
